(57) **CLAIM**

The ornamental design for a variable locking syringe assembly as shown and described.

DESCRIPTION

FIG. 1 is a top perspective view of a variable locking syringe assembly of the present disclosure;

FIG. 2 is a bottom perspective view of the device of FIG. 1;

FIG. 3 is a front view of the device of FIG. 1;

FIG. 4 is a back view of the device of FIG. 1;

FIG. 5 is a left side view of the device of FIG. 1;

FIG. 6 is a right side view of the device of FIG. 1;

FIG. 7 is a top view of the device of FIG. 1;

FIG. 8 is a bottom view of the device of FIG. 1;

FIG. 9 is a perspective front view of the device of FIG. 1, with the plunger partially retracted from the syringe body; and,

FIG. 10 is a perspective front view of the device of FIG. 1, with the plunger fully removed from the syringe body.
